UNITED STATES PATENT OFFICE.

IRWIN E. DEARSLEY, OF RACINE, WISCONSIN, ASSIGNOR TO WALKER MANUFACTURING COMPANY, OF RACINE, WISCONSIN, A CORPORATION OF WISCONSIN.

LIFTING JACK.

Application filed August 14, 1924. Serial No. 732,040.

To all whom it may concern:

Be it known that I, IRWIN E. DEARSLEY, a citizen of the United States, residing at Racine, in the county of Racine and State 5 of Wisconsin, have invented certain new and useful Improvements in Lifting Jacks, of which the following is a specification.

This invention relates to the class of devices known as lifting jacks, and more particularly to such a device designed to have 10 an exceptionally long lift in proportion to its size and height when in lowered or collapsed position.

While the uses for such a jack are innumerable, it is especially adapted for advantageous use with the oversize or balloon tires now used extensively on motor vehicles. For this use it is desirable to have 15 a jack which is compact and of small vertical height when lowered, in order to be placed under the low axle or other frame part when the tires collapse, and capable of 20 a comparatively long lift to elevate the car above its normal driving height in order 25 that the tire may be changed.

The jack is of that type employing a plurality of screw threaded members working one within another and each contributing 30 its share to the total lift of the jack. According to the embodiment of the invention here shown, the jack comprises a pair of non-rotary screws, one of which is stationary and the other vertically movable to lift the load. A hollow sleeve surrounds 35 the two screws when the jack is lowered, and has integral nuts formed in its two ends to engage the two screws respectively. Rotary means mounted in a fixed standard engages the outer surface of the sleeve to rotate same, and at the same time allows the 40 sleeve to move vertically upon the stationary screw.

The object of the invention is to provide 45 a jack, operating as briefly noted above and as set forth in more detail hereinafter, which is simple and compact and capable of lifting heavy loads with little effort.

Other objects and advantages of the invention will be readily apparent from the 50 following detailed description of one approved form of the apparatus.

In the accompanying drawings:

Fig. 1 is a central vertical section through the jack, taken substantially on the line 1—1 55 of Fig. 3.

Fig. 2 is a transverse section through the jack.

The right-hand portion of Fig. 2 is taken substantially on the line 2—2 of Fig. 1, and the left-hand portion is taken on an 60 inclined plane substantially indicated by the line 2—2 in Fig. 3.

Fig. 3 is an elevation of the jack on a somewhat smaller scale.

The stationary standard of the jack comprises a base plate 1, an integral bracket 2 for supporting the driving worm herein-after described, and a hollow vertically extending sleeve member 3. The sleeve 3 may conveniently be made as a separate unit and 65 secured to the base plate 1 by screws 4. The sleeve 3 is exteriorly threaded throughout substantially its entire height. An interior screw 5, which supports the load, is freely movable vertically through the sleeve 75 3. A load-supporting cap 6 is rockingly mounted at the upper end of screw 5, so that it may tilt slightly to accommodate itself to a tilting load.

A rather thin hollow metallic sleeve 7 is 80 loosely mounted between the inner screw 5 and the threaded sleeve 3. The tube 7 has diametrically disposed vertical slots 8, in which travel pins or projections 9 extending from the lower end of the inner screw 5. Lugs 10 formed on the lower end of tube 7, travel up and down in slots or grooves 11 85 cut in the inner surface of sleeve 3. It will be noted that the inner screw 5 and tube 7 are locked at all times against relative rotation by the engagement of pins 9 in slots 8. At the same time the tube 7 is held against rotation by the engagement of its lugs 10 in the slots 11 in the stationary sleeve 3. By this means screw 5 90 is never allowed to rotate, although it may be lifted vertically completely out of the threaded sleeve 3.

A hollow tubular member 12 surrounds the two screws as hereinabove described and 100 is provided in its lower end with an integral nut 13 meshing with the stationary screw 3, and in its upper end with a smaller nut 14 meshing with the inner screw 5. This sleeve 12 serves as a worm-wheel, and for 105 this purpose is provided with a series of vertical teeth 15 extending parallel with the axis of the sleeve or tube throughout substantially its entire length.

The driving worm 16 is mounted on an 110

inclined axis, as shown more particularly in Fig. 3, in bearings 17 and 18 at the upper end of bracket 2. An anti-friction thrust bearing 19 is provided between the 5 worm 16 and the bearing 18, and a socket 20 to accommodate one end of any suitable form of removable crank handle, is secured to the upper end of the supporting shaft 21 for the worm.

- 10 With the parts constructed and assembled as shown in the drawings, if the operating crank is turned continuously in a clockwise direction the sleeve 12 will be continuously rotated in a counter-clockwise direction as viewed from above. This will cause the sleeve 12 to elevate itself along the stationary screw 3 due to the engagement of the nut 13 in the sleeve 12 with this screw 3. The sleeve 12 will carry the inner 15 screw 5 bodily upward therewith. At the same time, since the inner screw 5 is held from rotation by the tube 7, and the nut 14 in the upper end of sleeve 12 is rotating, the inner screw 5 will be moved upwardly 20 with relation to the sleeve 12. The total lift of the jack is limited by the engagement of the top of tube 7 with the under side of nut 14, while pins 9 are engaged with the upper ends of slots 8. It will be 25 noted that in this position of the parts the inner screw 5 is lifted completely out of the standard 3, although the connecting tube 7 is always completely housed within the standard 3 and the outer sleeve 12. Rotation of the operating handle in the reverse 30 direction will return all of the parts to their initial position, in which both screws 3 and 5 are completely housed within the outer sleeve 12.
- 35 The inclined position of the driving worm enables it to mesh properly with the straight vertical teeth of the worm-wheel 12, and at the same time places the worm shaft 21 at the proper angle for engaging 40 the removable handle which could incline upwardly to a convenient operating position. The straight vertical teeth 15 on the worm-wheel slide freely up and down through the worm, as sleeve 12 moves vertically, and these straight teeth are more economical to manufacture than the ordinary curved worm-wheel teeth. The use of the 45 combination worm and screw drive for elevating the lifting member gives a great mechanical advantage, so that extremely heavy 50 loads may be elevated with comparatively little effort. The component parts of the jack are simple, substantial and easily assembled, and when the jack is in lowered position nest compactly one within the other.

I claim:

1. A lifting jack comprising a standard

and a lifting member having screw-threaded engagement with one another, the lifting member having continuous vertically extending gear teeth on its outer cylindrical surface, and a driving worm meshing with the vertical gear teeth and mounted on the standard on an inclined axis, so that those portions of the worm threads which engage the gear teeth are also vertically extended. 65

2. A lifting jack comprising a standard having an exteriorly screw-threaded portion, a lifting member interiorly threaded to engage this portion and provided on its outer cylindrical surface with a series of continuous vertically extending gear-teeth, a driving worm mounted on the standard on an inclined axis so that those portions of the worm threads engaging with the gear-teeth are also vertically extended, and an attaching member for an upwardly inclined removable handle at the upper end of the worm. 75

3. A lifting jack comprising a standard having a screw-threaded portion, a load-supporting screw freely movable longitudinally through the standard, means for holding the screw against rotation, a hollow sleeve surrounding the screw and standard, and interiorly threaded at opposite ends to engage the screw and standard respectively, and driving means mounted on the standard for rotating the sleeve. 85

4. A lifting jack comprising a standard having a screw-threaded portion, a load-supporting screw freely movable longitudinally through the standard, means for holding the screw against rotation, a hollow sleeve surrounding the screw and standard, and interiorly threaded at opposite ends to engage the screw and standard respectively, the outer surface of the sleeve being provided with longitudinally extending gear teeth, and a driving worm mounted on the standard and engaging the teeth on the sleeve. 90

5. A lifting jack comprising a standard having a screw-threaded portion, a load-supporting screw freely movable longitudinally through the standard, means for holding the screw against rotation, a hollow sleeve surrounding the screw and standard, and interiorly threaded at opposite ends to engage the screw and standard respectively, the outer surface of the sleeve being provided with longitudinally extending gear teeth, a driving worm mounted on the standard on an inclined axis and meshing with the teeth on the sleeve, and an attaching member for a removable handle at the upper end of the worm. 105
